UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SUSPENSION MEANS FOR TUBE FRAMES.

Application filed September 28, 1922. Serial No. 591,169.

This invention relates to tube frames such as are used in weaving tufted fabrics like Axminster carpets and is intended to provide an efficient and thoroughly reliable suspension means of simple and inexpensive construction for detachably suspending the tube frame from its carrier chains which support and carry it into position for temporary transfer for the operation of delivering the tufts to the fabric being woven.

In my co-pending application Serial No. 541,336, Patent No. 1,469,180, I disclosed a suspension means comprising pivotally related rigid or non-flexible arms forming a pair of co-operating suspension members which, while operating very satisfactorily, required considerable machining to adapt them for proper assembling, thereby involving considerable expense to manufacture. As hundreds of these tube frames are used for a single Axminster loom, the expense of such machining becomes an important consideration.

The present invention aims to overcome this drawback by providing suspension means so constructed and arranged as to permit the parts being made of pressed steel or die-formed material so constructed and arranged as to permit assemblage for use without the necessity of resorting to expensive machining of the parts. To this end I have so formed the suspension members in the stamping or punching operation that they are adapted to mutually interlock, with their interlocking portions held in operative relationship merely by the insertion of a fulcral pin which may be kept in fixed position by the thrust of the compression spring exerted upon the parts. The seating of the compression spring in a socket member, which is utilized also to secure the tube-attaching car or bracket to the main suspension member, forms another feature of the invention.

These and other features of the invention will be particularly described in the following specification and will be defined in the claims annexed.

In the accompanying drawings I have illustrated a preferred form embodying the principles of this invention, in which:

Figure 1 is an end elevation of the suspension means.

Figure 2 is a side elevation thereof.

Figure 3 is a vertical central section on a plane parallel to that of Figure 2.

Figure 4 is an elevation showing the inside face of the hanger with the lower looped end of the hook arm projecting inwardly through a recess in the hanger arm.

Figure 5 is a plan view.

Figure 6 is a detail in elevation of a modification of the tube-attaching bracket.

In the practice of the invention, according to the illustration in the drawings, I provide a main suspension member 1, made of sufficiently heavy stock to be practically rigid or non-flexible in service. This main suspension member 1, is formed with an upward projection 2, which is perforated to receive the journal of the yarn spool *c* indicated in dotted lines to form a bearing therefor. The extreme upper part of the main suspension member 1, is outwardly offset and projects upward to form a penetrating finger or extension 3, adapted to pass between the links *a* of the supporting carrier chain and to be detachably connected thereto by the hooked portion 7, of the co-operating pivotal suspension member 6.

The main suspension arm 1, has its lower end bent at substantially right angles to the upper portion to form an ear or lug 4, adapted to pass inside the hollow end of the carrier bar *b* shown in dotted lines in Figure 3, which supports the individual tuft tubes, also indicated in dotted lines in said Figure 3. At or adjacent to the right angle bend at the lower end of the suspension member 1, is formed an aperture 5, of a size to receive the curled end 8, of the pivotal suspension member 6, so that said curled-over end 8, forms a bearing which, after insertion through the aperture 5, is adapted to receive a fulcral pin 12, which is driven into it inside the plane of the inner face of the suspension arm 1.

To serve as a companion member to the tube-attaching portion 4, there is provided a tube-attaching bracket 9, whose outer end is bent at right angles to form a depending or vertical arm 10, the middle portion of whose lower end is notched or punched out to provide short extensions 11, which extend far enough downward to engage the opposite ends of the fulcral pin 12, to hold it

against vertical movement and which extensions 11, also engage the side edges of the curled bearing portion 8, of the pivotal arm 6, so as to aid in preventing a lateral 5 or axial play thereof. The aperture 5, and the corresponding notch in the tube-attaching bracket 10, may be so proportioned as to form a fairly close engagement with the exterior circular portion of the bearing eye 10 or loop 8, to afford additional means of preventing vertical movement of the fulcral pin.

It will be understood that, as in my earlier above-mentioned application, the pivotal 15 suspension member 6, is made of practically rigid or inflexible material so far as concerns the strains of actual service, and is normally thrust outward by means of a suitable spring such as the helical spring 20 15, seated in the socket member 13 and abutting against the inside face of the arm 6, which latter may be provided with an upset boss 16, to serve as a guide to keep the adjacent end of the spring centralized.

25 Since the fulcral or supporting pin 12 which forms the axis of movement of the hook arm 6 lies inside the end of the tubular carrier bar *b* when the parts are assembled it will be seen that the carrier bar itself 30 acts, through its opposite side walls, to prevent endwise displacement or removal of the axial pin. The parts are assembled as shown in Figures 2 and 6 before the bar-attaching portion of the hanger is inserted 35 within the tubular carrier bar. The bearing eye or hook 12 of the pivotal arm and its axis are therefore, by such interior location, protected against injury or displacement and yet the parts can be easily disassembled by removing the fastening screws 40 attaching the arms 4 and 9 with the carrier bar.

The socket member 13, has its outer end somewhat reduced to pass through registering apertures in the parts 1 and 10, and adapted to be headed up from the outside so that it forms in effect a hollow rivet serving to firmly unite tube-attaching bracket 9, with the suspension arm 1, and also serving as a socket for the thrust spring 15, by which the thrust spring is securely held in operative position. This permits the use of a spiral spring of substantial length thereby prolonging the life of the spring. The pivotal or hook member 6, is provided with aperture 6^a in registry with the journal of the spool *c* so that the projecting end of the journal does not interfere with the full inward movement of the hook member.

60 As shown in Fig. 6 the main arm or member 1^a may be struck up to form a transverse recess 20 which serves as a transverse bearing recess or socket for the reception of the fulcral pin 12.

65 It will be observed by reference to Fig-

ures 1 and 3 of the drawings that the hook arm 6, has its upper portion perforated at 6^a in line with the bearing aperture of the bearing ear 2 so as to permit full movement of the hook inwardly without obstruction 70 from the projecting spool journal which is thus allowed to penetrate the hook arm when the latter moves to its innermost position.

What I claim is:

1. Suspension means for a tuft tube frame embracing in combination, a pair of pivotally related suspension members one of which is secured to the tube frame carrier bar, the other member being formed with a bearing eye so disposed as to project through an aperture in the first-mentioned member sufficiently to allow insertion of a fulcral pin through said eye on the inner side of said first mentioned member, a fulcral pin inserted in said eye, and a spring engaging both members to oppose yielding resistance to the opening apart of their chain-engaging ends and acting to keep the fulcral pin seated in operative position. 75 80 85 90

2. Suspension means for a tuft tube frame embracing in combination, a pair of pivotally related chain-engaging suspension members, one of which is rigidly secured to the tube frame carrier bar, said members being pivotally and detachably interlocked by a fulcral pin extending through an eye formed on the pivotal member, and a spring arranged to oppose a yielding resistance to the opening apart of the chain-engaging ends 95 100 105 of the suspension members while also serving to maintain proper pivotal connection between the two suspension members, substantially as described. 110

3. Suspension means for a tuft tube frame embracing in combination coacting pivotally related chain-engaging members one of which is rigidly secured to the tube frame carrier bar, the other member being held by a pivotal connection with said first-mentioned member under spring tension, and a spring arranged to press the chain-engaging ends of said members yieldingly together and acting also to maintain their pivotal connection against displacement, substantially as described. 115 120

4. Suspension means for a tuft tube frame embracing in combination, a main suspension arm rigidly secured to the tube frame carrier bar, a bracket, a tubular stud uniting said bracket to said arm and acting as a spring-receiving socket, a rigid chain-engaging arm pivotally connected to said main suspension arm and normally thrust into chain-retaining position by the thrust of 125 said spring, substantially as described.

5. Suspension means for a tuft tube frame embracing in combination, a main suspension arm secured to the carrier bar of the tube frame, a spring-containing socket mem- 130

ber secured to said arm, a rigid chain-engaging arm pivotally connected with said first-mentioned arm, and a spring seated in said socket to normally force said chain-engaging arm into interlocking engagement with the carrier chain from which the tube frame is suspended, substantially as described.

6. Suspension means for a tuft tube frame
 10. embracing in combination, a main suspension arm provided with means for firmly securing it to the carrier bar of the tube frame at its lower end and with a bearing opening at its upper end to receive the journal of a
 15. yarn spool, a non-flexible chain-engaging arm pivotally disposed in relation to said main arm and provided with an aperture in line with the spool journal to allow said pivotal arm full pivotal movement unobstructed by the projecting end of said journal when the pivotal arm is moved back to chain-releasing position, and a spring acting to normally force said pivotal arm to chain-retaining position, substantially as described.

7. Suspension means for a tuft tube frame embracing in combination, a main suspension arm provided with means for supporting the yarn spool and the carrier bar of a
 20. tube frame, a chain-engaging arm provided with a chain-engaging hook at one end and having its other end bent around to form a fulcral eye, a fulcral pin passed through said eye to engage the inner side of the main suspension arm and a spring interposed between the two arms so as to force both ends

of the pivotal arm toward the main supporting arm, substantially as described.

8. Suspension means for a tube frame 40 embracing in its construction a chain-penetrating arm provided at its lower end with an inwardly projecting attaching member for securing it to the inside of a tube-frame carrier-bar, a separate upper attaching member comprising an angle bracket adapted to 45 form an additional connection between said arm and said carrier bar, both the arm and the bracket having partly registering slots, a pivotal hook latch fulcrumed in said slots and a spring acting normally to press the 50 hook end of said latch into suspension engagement with a carrier chain.

9. In a loom, a pattern chain, a supporting tube, a spool bearing bracket secured thereto, a substantially rigid chain-engaging 55 hook pivotally mounted on said bracket and extending within the tube, and means to force said hook yieldingly outward.

10. In a tuft tube frame for weaving, the combination of a tubular carrier bar, a suspension hanger rigidly secured to the end of the bar, said hanger being provided with an aperture opposite the open end of the bar, a hook having its lower end portion offset to be inserted through said aperture for 60 pivotal connection with the bracket and a coiled spring seated inside the tubular carrier bar to force the hook yieldingly outward.

In witness whereof, I have subscribed the 70 above specification.

EDGAR F. HATHAWAY.
